[57] CLAIM

The ornamental design for a lighting fixture, substantially as shown and described.

DESCRIPTION

FIG. 1 is a perspective view of the lighting fixture showing my new design, the fluorescent lamps being pivoted inward to a stored position;

FIG. 2 is a right side elevational view of my new design with the fluorescent lamps being pivoted outward to an extended position, the left side being a mirror image;

FIG. 3 is a front elevational view thereof;

FIG. 4 is a top plan view thereof;

FIG. 5 is a bottom plan view thereof;

FIG. 6 is a rear elevational view thereof.
